UNITED STATES PATENT OFFICE.

ELMER O. PARR, OF GLASFORD, ILLINOIS.

MEASURING INSTRUMENT.

1,119,450.

Specification of Letters Patent.

Patented Dec. 1, 1914.

Application filed October 29, 1913. Serial No. 798,100.

To all whom it may concern:

Be it known that I, ELMER O. PARR, a citizen of the United States, residing at Glasford, in the county of Peoria and State of Illinois, have invented certain new and useful Improvements in Measuring Instruments, of which the following is a specification, reference being had to the accompanying drawings.

10 This invention comprehends certain new and useful improvements in measuring instruments and has for its primary object to provide a device of this character which may be readily adjusted and which may be placed in compact form when not in use.

Another object is to provide a device of this character which may be composed of a plurality of telescopic sections and which will be extremely simple and cheap to 20 manufacture.

Another object is to provide an adjustable measuring instrument which may be employed as a try-square and which will be constructed in such manner that one arm 25 thereof may be adjusted longitudinally and at any desired angle to the remaining arm.

A further object is to construct the instrument in such manner that the sections of the adjustable arm may be readily moved 30 within one another for a limited distance in either direction and when in their innermost position may be folded against and parallel to the other arm of the device, the outer longitudinal edges of the sections of 35 the adjustable arm being in alinement.

A still further object is to generally improve and simplify the construction and operation of devices of this character and increase the efficiency thereof without 40 increasing the cost of the same.

With the above and other objects in view, my invention consists in certain novel constructions, combinations, and arrangements of parts to be hereinafter more fully described, claimed, and illustrated in the accompanying drawings, in which,

Figure 1 is a plan view of the tool extended; Fig. 2 is a similar view with the tool in closed position; Fig. 3 is a fragmentary bottom plan view of the adjustable arm; Fig. 4 is a fragmentary side elevational view of the stationary arm; Fig. 5 is an enlarged detail perspective view of one end of the inner section of the adjustable arm; and Fig. 6 is a sectional view on the line 6-6 of Fig. 2.

Referring more specifically to the drawings in which similar reference characters designate corresponding and like parts throughout the several views, 1 designates the stationary arm or handle which is preferably of rectangular form in cross section and which has one end beveled, as shown at 2, with the inner side of the section cut away at this end, as shown at 3.

The adjustable arm of the instrument is composed of a plurality of telescoping sections numbered 4, 5, and 6, said sections being substantially U-shape in cross section with the free marginal edges of the lower 60 walls in alinement, the free marginal portions of the upper walls of the sections being inclined forwardly and downwardly and terminating at a predetermined distance above and inwardly of the free longitudinal edges of the bottom walls of the sections. The inclined front portion of each section is provided with suitable graduation marks 7 upon its upper face and along its forward edge to indicate inches and fractions of 70 inches, whereby the length of the adjustable arm may be readily adjusted and the forward marked edge thereof employed as a 80 rule of any desired length.

The first or inner section 4 of the adjustable arm of the tool is provided with a pair of rearwardly directed ears 8 formed by cutting the rear vertical portion of said section near its inner end and bending the material outwardly, as will be clearly understood. The pivot pin 9 is passed through the ears 8 and the upper and lower portions of the stationary arm or handle 1, at a suitable point along the inner edge of said stationary arm or handle 1 a short distance 90 from the forward end of the same, as will be readily understood by referring to the drawing. It will also be seen that by connecting the adjustable and stationary arms in this manner, said adjustable arm may be 95 swung to position against the inner face of the stationary arm or handle 1 and parallel with the latter when the device is not in use. Further, the adjustable arm may be swung at any desired angle with respect to the stationary arm or handle 1 and the angle indicated by the position of the inner forward corner of the stationary arm or handle 1 upon the scale 10 upon the upper face of 100 said first or inner section 4 of the adjustable arm.

Each of the sections 5 and 6 of the adjust-

able arm is limited in its outward movement by the stop lugs 11 on the lower face of the bottom portion thereof and engaged in the longitudinal elongated guide slots 12 in the lower portion of the section within which the first section slides, it being understood that each of the sections except the outer one is provided with a slot 12.

Each of the slideable sections constituting 10 the adjustable arm of the tool is also provided with an outwardly and upwardly directed tongue 13 formed on the lower edge of the inclined front portion of said section, for the purpose of forcing the slideable sections outwardly for a short distance in order 15 that they may be grasped and pulled upwardly until the stop lugs 11 reach the outer ends of the slots 12 within which they are engaged. It will be understood that the 20 tongues 13 are preferably located near the inner ends of the slideable sections and are arranged in such manner that when the device is in closed position, as shown in Fig. 2, said tongues 13 will be spaced from one another in order that they may be readily engaged separately, whereby either of the sections 5 and 6 may be readily forced outwardly and it will be understood that while 25 the sections 4, 5, and 6 may be of any desired length, I prefer to have each section 4 preferably substantially six inches in length and have the length of the slots 12 so that when the sections 5 and 6 are in their extended positions, each of said sections 5 and 30 6 extends into the section within which it slides for the distance of substantially one inch, the graduation marks on said sections 5 and 6 being regulated accordingly to form the complete rule when the sections of the 35 adjustable arm are extended to their outermost positions.

The adjustable arm may be readily regulated in adjusted position with respect to the stationary arm or handle 1 by any suitable 40 lock nut 14 threaded upon one end of the pivot pin 9.

If desired, a spirit level 15 may be positioned in the stationary arm or handle 1 as will be clearly understood.

50 While I have shown the preferred embodiment of my invention, it will be understood that minor changes in the details of construction and arrangement of parts may be made within the scope of the appended 55 claims without departing from the spirit of my invention or sacrificing any of the advantages of the same.

What I claim is:—

1. A device of the character described comprising a plurality of telescoping sections, each of said sections being substantially U-shape in cross section, the free longitudinal marginal portions of the lower walls of said sections being in alinement.

60 2. A device of the character described comprising a plurality of telescoping sections, each of said sections being substantially U-shape in cross section, the free longitudinal marginal portions of the lower walls of said sections being in alinement, the free longitudinal marginal portions of the upper walls of the section being inclined downwardly and forwardly and terminating a predetermined distance inwardly of the 70 longitudinal edges of the lower walls of the sections.

3. A device of the character described comprising a plurality of telescoping sections, each of said sections being substantially U-shape in cross section, the free longitudinal marginal portions of the lower walls of said sections being in alinement, the free longitudinal marginal portions of the upper walls of the sections being inclined 80 downwardly and forwardly and terminating 85 a predetermined distance inwardly of the longitudinal edges of the lower walls of the sections, and means carried by the inclined portions of certain of the sections adjacent their outer extremities whereby relative 90 movement may be imparted to the sections.

4. A device of the character described comprising a plurality of telescoping sections, each of said sections being substantially U-shape in cross section, the free longitudinal marginal portions of the lower walls of said sections being in alinement, the free longitudinal marginal portions of the upper walls of the sections being inclined 95 downwardly and forwardly and terminating 100 a predetermined distance inwardly of the longitudinal edges of the lower walls of the sections, and upwardly disposed tongues carried by the inclined portions of certain 105 of the sections adjacent their outer extremities whereby relative movement may be imparted to the sections.

In testimony whereof I hereunto affix my signature in the presence of two witnesses.

ELMER O. PARR.
